Patented Sept. 16, 1913.

UNITED STATES PATENT OFFICE.

THOMAS C. HOLSCLOW, OF HORSESHOE, NORTH CAROLINA, ASSIGNEE OF ONE-HALF
TO O. W. CLAYTON AND ONE-HALF TO W. H. FAULKNER, OF BEVARD, NORTH
CAROLINA.

ROOFING-TOOL.

1,073,580.

Specification of Letters Patent. Patented Sept. 16, 1913.

Application filed February 7, 1913. Serial No. 676,000.

To all whom it may concern:

Be it known that I, THOMAS C. HOLSCLOW, a citizen of the United States, residing at Horseshoe, in the county of Henderson and 5 State of North Carolina, have invented certain new and useful Improvements in Roofing-Tools; and I do hereby declare the following to be a full, clear, and exact description of the invention, such as will enable 10 others skilled in the art to which it appertains to make and use the same.

This invention relates to tools and more particularly to roofing tools.

An object of the invention is to provide a 15 roofing tool which may be readily employed for trimming, bending and crimping the tin along the valleys, and especially for trimming the shingles after they are placed and secured.

20 A further object is to provide a tool which will perform the above mentioned duties without the necessity of removing the shingles for trimming them.

25 Other objects and advantages will be hereinafter set forth and pointed out in the specification and claims.

In the accompanying drawings which are made a part of this application, Figure 1 is a side view of the tool, the upper portion of 30 the handles being broken away. Fig. 2 is a top plan view, the handles being also broken away in this view. Fig. 3 is a cross sectional view on the line 3—3 of Fig. 1, Fig. 4 is a cross sectional view on the line 4—4 of 35 Fig. 1, and Fig. 5 is a fragmental plan view of a roof and its valley, with my improved roofing tool in operative position.

Referring more particularly to the drawings in which similar reference numerals 40 designate corresponding parts throughout the several views, 1 represents the handles which are pivoted together by means of the bolt 2 and are parallel to one another when the tool is in closed position. The portions 45 of the handles 1 are curved slightly and formed into co-operating blades 3, as clearly shown for trimming the edges of the shingles, as will be clearly understood. One of the handles 1 is formed with a hammer projection 4 which is adapted to serve for driving nails through the shingles, hammering the seams down, etc.

Each handle 1 carries a pair of jaws 5 formed thereon, said jaws projecting from

opposite sides of the handle, one jaw carried 55 by each handle being higher than the other jaw of said handle. The jaws carried by the opposite handles, however, are adapted for close engagement against one another when the tool is in closed position. The jaws 60 may be readily locked in closed position by means of the thumb screw 6 carried by one handle and adapted to have its point engaged within the opposite handle. Between the thumb screw 6 and the pivot bolt 2, each 65 handle carries a bifurcated block 7 upon its side, having a V-shape channel 8 between the arms 9.

Heretofore it has been necessary to place the shingles in their proper positions and 70 mark them, then remove the shingles and trim the same and bend or crimp the edges thereof, after which they were replaced and nailed in position for the operation of uniting them with the valley-strip, by a seam, in 75 the usual manner. When using this new tool, however, each shingle is placed in position and nailed, with the hammer projection 4 or any suitable tool for this purpose, and it is thereupon ready for the trimming 80 and bending operations which may be performed by the blades 3 and jaws 5 respectively.

The shingle having been nailed in place and turned, the projecting edge thereof is 85 then caught between the jaws 5, and the tool is now turned for bending said edge downward, under the upturned and inclined edge of the valley strip. The tool may then be closed, so that the closed converging jaws, 90 as shown in Fig. 3, may be employed for hammering the down turned edge sufficiently under the said up-turned edge of the valley to allow the operator to clamp the bent under edge of the tin shingle and 95 clench or crimp said bent-under edge tightly upon said up-turned edge, whereupon, the handles are swung in the direction of said edge, while the jaws are gripping the same, so that the bifurcated blocks 9 are caused to 100 impinge upon the down-turned edge of the shingle, so as to bend it under said up-turned edge. Obviously, by repeatedly changing the gripping position of the jaws 5, and each time swinging the handles laterally, as described, the depending edge of the shingle is turned under in advance of the gripping jaws.

In Fig. 5, the tool is shown in position with its gripping jaws clamping the seam 13 while the bifurcated lugs 9, of one side of the tool, are pressing the edges of two contiguous shingles under the upstanding edge 13' of the valley 14. In this view, the shingles 15 and 16 have been trimmed and bent under the edge 13' and partially clenched or crimped thereunder, the tin shingle 17 has been trimmed, but not turned down or under, and the shingle 18 has been secured in place, but has not been trimmed or turned. After the seam 13 has been formed, as described in the foregoing, it may then be hammered down parallel with the side of the valley on which it is formed, and this operation may be performed by means of the poll or hammer element 4.

The coöperating plates or nippers 3 and clamping jaws 5 are automatically separated upon the release of the pressure upon the outer ends of the handles 1, by means of the leaf spring 10 resting within the channel 11 provided therefor in the lower clamping jaw 5, the forward end of the spring 10 being secured in position in the channel 11 by means of a suitable screw 12 or other fastening device while the rear end of the spring projects beyond the jaw 5, it being understood that the spring is positioned between the lower and upper jaws. When the outer ends of the handles 1 are drawn together, forcing the clamping jaws 5 toward one another, the spring 10 is bent by the jaws and forced into the channel 11 provided there-

for in the upper face of the lower jaw 5 when said jaws are pressed tightly together.

It will thus be seen that I have provided a roofing tool which will be highly efficient in the performance of its duties and which is of such construction that it may be readily and cheaply manufactured.

What I claim is:—

1. A tool comprising pivotally united handles having coöperating clamping jaws upon one side, and bifurcated bending and crimping blocks carried by the handles for coöperation with the clamping jaws.

2. A tool comprising handles pivotally connected to one another, bending and crimping blocks carried by said handles, and clamping jaws projecting from said handles and adapted for coöperation with the bending and crimping blocks.

3. A roofing tool comprising pivoted handles having coöperating clamping jaws upon one side, bifurcated guide blocks carried by the handles for coöperation with the clamping jaws, said clamping jaws being adapted to be pressed toward one another, and means positioned between the jaws for automatically separating the latter.

In testimony whereof I have signed my name to this specification in the presence of two subscribing witnesses.

THOMAS C. HOLSCLOW.
